MULTIBLADED DISK KNIFE SLITTING
MECHANISM

Howard A. Burdwood, Portland, Maine

Application December 10, 1947, Serial No. 790,765

1 Claim. (Cl. 164—60)

1

This invention relates to a machine for slitting sheet material so as to form simultaneously a plurality of narrow strips, such strips being preferably of uniform width.

It is an object of the invention to provide a machine for cutting cloth, paper, leather, or other equivalent sheet materials into strips for any desired purpose. For example, pieces of cloth are frequently cut into strips for the manufacture of hooked, crocheted or braided rugs. Cutting narrow strips from pieces of cloth by the use of ordinary scissors is slow and tedious and usually results in strips of more or less irregular width. According to the present invention, a slitting mechanism is provided which slits the marginal portion of a sheet into a plurality of narrow strips. This mechanism is characterized by a rotary cutter having a plurality of disk blades which are coaxial and are uniformly spaced apart. A press roll is pressed tangentially against the blades, the press roll being pivotally supported by a floating connection so that its pressure against the individual blades is equalized. A work table is also provided in conjunction with a knife and press roll.

The mechanism embodied in the invention is designed for economy, efficiency and ease of assembly and adjustment.

Further advantageous features of the invention will be apparent from the following description thereof and from the drawing, of which:

Figure 1 is an elevational view of a mechanism embodying the invention;

Figure 2 is a section on line 2—2 of Figure 1; and

Figure 3 is a rear elevational view of the mechanism shown in Figure 1.

The slitting mechanism illustrated on the drawing comprises a main frame 10, which includes a downwardly-extending bracket 12 having a clamp screw 14 threaded through the extremity thereof so as to facilitate the clamping of the machine on an ordinary table 16. Mounted on the frame 10 is a work table 20 which has a rectangular aperture 22. A rotary knife 24 is rotatably mounted beneath the table 20 so that its top projects up through the aperture 22. This knife is mounted on a horizontal shaft 26 which is journaled in the frame 10 and is provided with an operating crank 28, having a crank handle (not shown) at its extremity. The knife 24 is mounted on a portion 30 of the shaft 26 of reduced diameter, being clamped in place by a wing nut 32 threaded on a reduced extension 35 40 of the shaft.

2

34 of the shaft. A suitable washer 36 may be employed between the nut and the knife 24.

As indicated in Figure 2, the knife preferably consists of a plurality of annular disk blades 40 with sharp circumferential edges arranged in coaxial, equally spaced relation. These blades are embedded in and secured together by a hub member 42 of suitable cast metal. This hub member 42 is cylindrical and is coaxial with the blades 40. The outside diameter of the hub member is necessarily less than that of the blades, the difference being sufficient to accommodate the thickness of the sheet material to be slit, but the hub diameter is preferably as great as is practical so as to fill the aperture 22 in the work table 20 and thus to minimize the possibility of the strips of material becoming tangled and jammed at the knife. The hub member 42 has an axial bore adapted to receive the reduced portion 30 of the shaft 26 with a close fit so that there is practically no lateral play between the knife 24 and the shaft on which it is mounted. Since the cast metal 42 may have a co-efficient of thermal expansion different from that of the blades, the blades are preferably made with circular grooves 44 in one or both faces. The inner diameter of the annular blades is preferably greater than the diameter of the bore of the hub member 42, so that except for the projecting circumferential portion of each blade, the entire blade surface is covered by the cast metal. When the hub member is cast so as to embrace the blades 40, the metal enters the grooves 44 and thus locks the several blades against any looseness with respect to the hub member.

A cylindrical press roll 50 is supported above the knife 24 and is adapted to press firmly against the cutting edges of the blades 40. This roll is rotatably mounted on a shaft 52 which extends between the arms 54 of a fork 56. The shank 58 of the fork is curved to support a shaft 60 which extends approximately parallel to the arms 54. The shaft 60 extends through and bears in the end portion 62 of an arm 64 which projects laterally from a bracket 66. Preferably, both end portions of the shaft 60 are secured in the fork 56, the shaft providing a pivotal or floating connection between the roll 50 and the bracket 66. The axis of the shaft 60 is at right angles to a plane containing the axis of rotation of the roll 50. Hence, the axis of this roll can rock freely so as to equalize the pressure of the roll against the individual blades 40. The roll 50 is pressed firmly against the

blades 40 by any suitable means such as a tension rod 70, one end of which is anchored in the main frame 10, as at 72, the other end being screw-threaded to receive a wing nut 74. The portion of the rod 70 adjacent to the wing nut passes through the bracket 66 near the extremity thereof where the arm 64 projects laterally therefrom. The bracket 66 is pivotally mounted on the frame 10, as at 76. By screwing down the nut 74, the pressure of the roll 50 against the blades 40 can be adjustably varied. If the nut 74 is removed from the rod 70, the bracket 66, with the roll 50 and connecting members, can be swung back out of the way of the knife 24 to facilitate the clearing of any jammed material or replacement of the knife.

Along the side edge of the table 20 adjacent to the aperture 22 is a guide rail 80 which may be secured to the table by a bolt 82 and wing nut 84. This guide rail can thus be adjusted so the portion remote from the end secured by the bolt 82 is moved toward or from the nearest blade 40, thus determining the width of the marginal strip cut from the work sheet which is sent through the slitter. This width is preferably the same as that of the strips cut between successive blades. If wider or narrower strips are desired, another rotary knife with differently spaced blades is substituted for the knife 24, and the guide 80 is adjusted accordingly.

For convenience and economy in manufacture slitting mechanisms, the main frame 10 and bracket 66 may be die-castings of a suitable metal alloy having sufficient mechanical strength. For example, an alloy containing 96% zinc and about 4% aluminum is suitable for these parts. A similar alloy can be used in casting the shaft 26 and crank 28 in one piece about a steel core which projects at the end of the shaft and is screw-threaded at 34. A similar alloy can be used for the hub member 42 of the rotary knife 24, the blades 40 being of "high-speed" steel, tempered and ground before being assembled. A suitable example of high speed steel is a steel containing 18% tungsten, 4% chromium, 1% vanadium and .75% carbon, but other high speed steels, such as those containing molybdenum with or instead of tungsten, are also satisfactory for the purpose. The melting point of the alloy is not high enough to soften or otherwise affect the blades adversely when the hub member is cast with a set of blades therein. The press roll is preferably of a hardened carbon

steel which is not scored by the cutting edges of the blades when pressed against them. It is to be understood, however, that the foregoing materials are referred to by way of illustration and that invention is not necessarily limited thereto.

What I claim is:

A slitting mechanism comprising a frame, a horizontal work table with an aperture secured on said frame, a multi-bladed disc-knife mounted below said table for rotation about a horizontal axis, said knife projecting up through said aperture slightly above the level of the table, a rotatable shaft journaled in said frame and carrying said knife, an operating crank in said shaft, a bracket pivotally secured at one end to said frame at one side of said shaft and extending above and beyond said shaft to the other side thereof, a tension member attached at one end to said frame on said other side of the shaft and adjustably attached to the free end of the bracket, an arm projecting from said bracket out over the table, a press roll supported on said knife and rotatable about an axis parallel to that of the knife, supporting means operatively connecting said press roll and arm whereby rocking movement of said bracket about its pivot moves said press roll to or from contact with said knife, and means on said tension member operable to draw the free end of said bracket downward so as to vary the pressure of said press roll against said knife.

HOWARD A. BURDWOOD.
